FIG 1

FIG 2

FIG. 1 is a side view of a shoe showing my new design;

FIG. 2 is a top view thereof.

The side not shown in FIG. 1 is substantially the same as the side shown and the bottom of the shoe is substantially plain. The dominant features of my design reside in the combination on the shoe disclosed of the ornamentation on the contrasting bands that extend across the vamp and on the sides of the quarter together with the intertwined ornamentation on the sides of the sole, all as shown.

I claim:

The ornamental design for a shoe, as shown and described.
